UNITED STATES PATENT OFFICE

WALTER J. MATT, OF UTICA, NEW YORK, ASSIGNOR TO UTICA CUTLERY COMPANY, OF UTICA, NEW YORK, A CORPORATION OF NEW YORK

DESIGN FOR A KNIFE HANDLE OR SIMILAR ARTICLE

Application filed June 28, 1930. Serial No. 36,221. Term of patent 7 years.

To all whom it may concern:

Be it known that I, WALTER J. MATT, citizen of the United States, residing at Utica, in the county of Oneida and State of New York, have invented a new, original, and ornamental Design for a Knife Handle or Similar Article, as shown in the accompanying drawing and described in the following specification, forming a part thereof.

Figure 1 is a side elevation of a knife handle or similar article showing my new design, and Figure 2 is a bottom plan view thereof.

The opposite side of the handle shown in Figure 1 is similar to that shown in the drawing.

I claim:

The ornamental design for a knife handle or similar article as shown and described.

WALTER J. MATT.
